UNITED STATES PATENT OFFICE.

HERBERT McCORNACK, OF LITTLEFALLS, NEW YORK.

ELASTIC-FLUID TURBINE.

SPECIFICATION forming part of Letters Patent No. 694,980, dated March 11, 1902.

Application filed January 3, 1899. Serial No. 700,935. (No model.)

To all whom it may concern:

Be it known that I, HERBERT McCORNACK, a citizen of the United States, residing in the city of Littlefalls, in the county of Herkimer, 5 State of New York, have invented certain new and useful Improvements in Elastic-Fluid Turbines, of which the following is a specification.

My invention relates to a turbine in which the turbine wheel is actuated by a jet of elastic fluid which is directed against the peripheral portions of the vanes or blades and in which the actuating fluid passes from the inner ends of the vanes or blades against which it primarily acts into the central space of the wheel.

One object of my invention is to utilize the *vis viva* of the jet of actuating fluid not only in acting upon the vanes against which the jet strikes primarily, but also in acting upon vanes on the opposite side of the wheel after passing the central space of the wheel.

Another object of my invention is to connect the wheel movably with its spindle or 25 shaft in such manner that it is self-balancing and shifts the position of its axis while rotating toward and from the axis of the shaft until the wheel is in perfect running balance.

In the accompanying drawings, Figure 1 is 30 a plan view of that side of the turbine wheel at which it is connected to its spindle. Fig. 2 is a horizontal section of the wheel and jet-nozzle in line 5 5, Fig. 4. Fig. 3 is a vertical section in line 3 3, Fig. 2. Fig. 4 is a side 35 elevation of the turbine and nozzle. Fig. 5 is a face view of a turbine wheel in which the spindle passes across the open central space of the wheel. Fig. 6 is a sectional view in line 7 7, Fig. 5.

40 Like letters of reference refer to like parts in the several figures.

A A' represent the disks of the turbine wheel, g the vanes or blades thereof, and z the short wings between the vanes.

45 h represents the jet-nozzle, which opens tangentially, or nearly so, against the peripheral face of the wheel between the disks A A' thereof. The bore of this nozzle is flat at its mouth, about as wide as the vanes between 50 the disks of the wheel, and comparatively narrow, so that the jet of actuating fluid is de-

livered against the wheel in a flat or oblong form. The bore of the nozzle is contracted at a short distance from its mouth and flares or diverges toward the mouth to such an extent that the actuating fluid, whether steam, compressed air, or other fluid, is expanded in passing from the contracted throat to the wide mouth of the nozzle and has its pressure converted into velocity, thereby delivering a jet 60 of maximum velocity and of oblong or flat form against the peripheral portions of the vanes. The bore of the nozzle diverges in a plane across the face of the wheel, as shown by dotted lines in Fig. 4, and it may be of 65 uniform size at right angles to that plane, as shown in full lines in Fig. 2, or it may converge or diverge at right angles to that plane, as may be preferred.

The outer portions of the vanes g are 70 straight and extend from the periphery of the wheel inwardly at an oblique angle to the radial line and stand at an obtuse angle to the axis of the nozzle when in front of the latter. The inner portions of the vanes curve or 75 turn toward the center of the wheel and point toward corresponding vanes on the opposite side of the center. The vanes terminate at a distance from the center of the wheel, leaving an open central space between the inner 80 ends of the vanes. The wings z are shaped and arranged like the straight outer portions of the vanes and are arranged between the same. These wings may, however, be omitted when not required.

85 In the construction of the wheel represented in Figs. 1 to 4 the spindle or shaft does not extend across the open central space of the wheel and the inner ends of the vanes deliver the jet across the middle of the central 90 space to the vanes on the opposite side of the center. In the construction of the wheel represented in Figs. 5 and 6 the spindle extends across the central space and the inner ends of the vanes point to one side of the spindle 95 and deliver the jet past the same to the vanes on the opposite side of the center. In either construction the inner ends of the vanes stand in such position that the jet of actuating fluid does not encounter any obstruction in passing from the inner end of the primary vane 100 across the central space of the wheel to the

inner end of the corresponding vane on the opposite side of the center, but passes unbroken across said space to the corresponding vane on the opposite side of the center.

5 In my improved turbine the actuating-jet is first expanded in the diverging nozzle, so that the pressure of the fluid is converted into velocity and a jet of maximum velocity is delivered against the wheel. This jet acts 10 by its *vis viva* upon the vane against which it impinges primarily, then passes unbroken across the central space of the wheel, and then acts again by its *vis viva* upon a corresponding vane at the opposite side of the 15 wheel. The actuating fluid is in this manner utilized in a very efficient and economical manner. By delivering the expanded jet in a flat or oblong form against the vanes the jet is delivered in the form which it tends to 20 assume upon impact and the losses in efficiency arising from cross-currents in the spreading of the jet after it reaches the vane are avoided. The oblong nozzle also delivers the jet as near the periphery of the wheel 25 as possible. The nozzle and the spaces between the vanes are preferably so proportioned that the actuating fluid does not fill these spaces, but flows upon and over the concave sides of the vanes as a thin film.

30 To render the turbine wheel self-balancing while rotating, the wheel is secured to its spindle or shaft by a frictional connection which allows the wheel to move toward or from the axis of the spindle until the wheel is in running balance. This connection is constructed 35 as follows: *S* represents the spindle or shaft, and *b* a hub secured to the upper end thereof by a screw-thread, as shown, or by other suitable means. This hub is provided with a 40 laterally-projecting thin circular flange *f*. The lower disk *A* of the turbine wheel is provided in its under side with a circular recess, somewhat larger in diameter than the flange *f* and receiving the latter, as shown in Figs. 45 1 and 3. *d* represents screws which enter threaded openings in the under side of the lower disk *A* and which project with their heads over the marginal portion of the flange *f*. The latter is provided on its upper side 50 with bosses *a*, which are arranged between the screws and bear against the under side of the lower disk *A*, rendering the portions of the flanges *f* between these bosses which do not bear against the disk somewhat springy 55 or yielding under the pressure of the screws. This provides a moderate and constant frictional constraint against the lateral movement of the wheel on the spindle, but allows the wheel to shift its position laterally on the 60 spindle when this frictional resistance is over-

come by the tendency of the wheel to seek the position in which it is in balance.

The disks *A A'* of the wheel are preferably provided in their opposing sides with grooves in which the edges of the vanes *g* and the 65 wings *z* are seated and secured by soldering or otherwise.

I claim as my invention—

1. The combination with a tangentially-arranged jet-nozzle, of an inward-and-outward-flow turbine wheel provided with a series of vanes having their outer portions extending obliquely inward across the radial lines of the wheel and their inner portions turned approximately radial and terminated short of 75 the axis of the wheel to form a central space, the force of the jet being extended upon said vanes primarily during its inward flow and secondarily during its outward flow substantially as set forth. 80

2. The combination with a tangentially-arranged jet-nozzle, of an impact turbine wheel having a series of curved or bent vanes extending inward from the periphery with inner ends turned approximately radial and terminated at a distance from the axis, and a central space communicating only with the passage-ways between said inner ends of the vanes substantially as and for the purpose 85 set forth. 90

3. The combination with the spindle, of a wheel thereon capable of movement toward and from the axis thereof, and rotatively secured thereto by frictional clamping means adapted to permit automatic lateral adjustment of the wheel on the spindle without rebounding action substantially as set forth. 95

4. The combination with the turbine spindle provided with an attaching-flange, of a turbine wheel having a recess larger than said flange for the reception of the same and which permits said wheel to move toward and from the axis of the spindle, and clamping devices connecting said flange and wheel, substantially as set forth. 100

5. The combination with the turbine spindle provided with an attaching-flange having projections on its upper side, of a turbine wheel having in its under side a recess larger than said flange for the reception of the same 110 and which permits said wheel to move toward and from the axis of the spindle, and clamping-screws connecting said flange and wheel and arranged between the projections of said flange, substantially as set forth. 105
